UNITED STATES PATENT OFFICE.

JOHN F. HUME, OF REDDING, CALIFORNIA.

SAFETY DEVICE FOR MINE-CHUTES.

1,184,958.

Specification of Letters Patent. Patented May 30, 1916.

Application filed January 10, 1916. Serial No. 71,293.

To all whom it may concern:

Be it known that I, JOHN F. HUME, a citizen of the United States, residing at Redding, in the county of Shasta, State of California, have invented a new and useful Safety Device for Mine-Chutes; and I do hereby declare the following to be a full, clear, and exact description of the invention, such as will enable others skilled in the art 10 to which it appertains to make and use the same.

The present invention relates to a safety device for mine chutes, and has for its object to provide a device of this character 15 which embodies novel features of construction whereby the mouth of the chute is closed at all times except when the ore or other material is being dumped through the same, thereby preventing the possibility of accidents due to workmen falling through unprotected chute openings.

Further objects of the invention are to provide a device of this character which is comparatively simple and inexpensive in its 25 construction, which can be readily applied to the mouth of any chute through which ore or like material is dumped from cars, which is automatically locked in a closed position when the car is moved away from the 30 chute, and which can be manipulated without difficulty by the same workman who usually manages the car and dumps the same.

With these and other objects in view, the 35 invention consists in certain novel combinations and arrangements of the parts as will more fully appear as the description proceeds, the novel features thereof being pointed out in the appended claims.

40 For a full understanding of the invention, reference is to be had to the following description and accompanying drawing, in which:—

Figure 1 is a side elevation of a safety device constructed in accordance with the invention, the mine car being shown by full lines as in position upon the track before being moved upon the turntable of the device, and by dotted lines as in position upon the 45 turntable. Fig. 2 is a top plan view of the device with the car removed, the turntable being shown by full lines in normal position, and by dotted lines in the position assumed when the mouth of the chute is uncovered 50 preparatory to dumping the contents of the car through the same. Fig. 3 is a transverse

vertical sectional view on the line 3—3 of Fig. 2. Fig. 4 is a similar view on the line 4—4 of Fig. 2, the turntable being in position for uncovering the mouth of the chute. 60 Fig. 5 is a detail view of the latch member which holds the turntable against rotation at all times except when the car is in position upon the same. Fig. 6 is a transverse sectional view on the line 6—6 of Fig. 2, the 65 inoperative position of the car locking arm being indicated by full lines, and the operative position thereof by dotted lines.

Corresponding and like parts are referred to in the following description and indicated 70 in all the views of the drawings by the same reference characters.

Referring to the drawings, the numeral 1 designates a platform upon which is mounted the usual track 2 for the cars 3, 75 said cars being formed with the dumping bodies 3^a. A circular bed 4 is arranged upon the platform opposite the end of the track 2, and a turntable 5 is pivotally mounted upon the bed 4, said turntable carrying a 80 track section 6 which can be turned into alinement with the main track 2 to admit of a car being moved from the track upon the turntable, and vice versa. The center of the bed 4 is provided with a raised seat 85 4^a and the bottom of the turntable 5 is provided with a corresponding seat 5^a, the said seats 4^a and 5^a being formed with annular raceways 7 within which ball bearings 8 are positioned. A pivot bolt 9 extends centrally 90 through the bed 4 and turntable 5, and the latter is supported upon the balls 8 so that it will rotate freely with a minimum amount of friction. The periphery of the turntable is provided with a depending annular flange 95 5^b which overhangs the edge of the bed 4.

The platform 1 and bed 4 are provided with corresponding openings forming the mouth 10 for an ordinary chute such as are commonly employed in mines. The turntable 100 5 is provided opposite the end of the track section 6 thereon with an opening 11 which is provided at the ends and outside thereof with the shield 12, and is adapted to be turned into and out of registry with the 105 mouth 10 of the chute. When the track section 6 of the turntable is in alinement with the main track 2, the chute mouth 10 is closed by the turntable 5, and this is the normal position of the turntable. However, 110 when the turntable is rotated about its axis to bring the track section 6 thereon into a

position at substantially right angles to the direction of the main track 2, as indicated by the dotted lines on Fig. 2, the opening therein is in registry with the chute opening 10, so that the contents of the mine car can be readily dumped through the chute opening. The turntable is then rotated back to normal position and the car rolled away from the main track for further loading.

10 Pivottally mounted at 13 upon one side of the track section 6 on the turntable, is a trip lever 14 which terminates in a downwardly projecting locking finger 15 passing loosely through an opening in the turntable 15 and adapted to engage a depression 16 in the bed 4. A spring 17 engages the trip lever 14, and normally holds the locking finger 15 in operative position. The opposite end of the trip lever is curved upwardly 20 to provide a trigger 18 which normally projects above the top of the rails into the path of the car wheels. When the car 3 is rolled into position upon the turntable, one of the front wheels thereof will engage the trigger 25 18 and force the same downwardly, thereby lifting the trip lever 14 against the action of the spring 17 and swinging the locking finger 15 into inoperative position. The turntable 5 is then released so that it can be 30 swung around through an angle of substantially 90° and brought into dumping position. After the contents of the car have been dumped through the chute opening the turntable is rotated to bring the track section thereon again into alinement with the main track 2 and the car rolled away for 35 reloading. As soon as the car is rolled out of engagement with the trigger 18 the spring 17 forces the trip lever 14 into operative position and again locks the turntable against rotation. A suitable stop member 19 may 40 be provided to limit the rotary movement of the turntable as it is turned backward to bring the track section thereon into alinement with the main track 2.

It may frequently be found desirable to provide some means for locking the car 3 upon the turntable when the latter is turned away from its normal position and the track 50 section 6 thereon is not in alinement with the main track 2. Blocks 20 may be suitably arranged upon the turntable 5 to check the forward movement of the car when it is rolled into proper position upon the turntable. Any suitable means such as the 55 swinging arms 24 may be provided to engage the car and lock the same against backward movement at all times except when the track section 6 of the turntable is in alinement with the main track 2. In the present 60 instance this arm 24 is carried by a longitudinally extending rock shaft 25 which is journaled within suitable bearings 26, the extremity of the arm being notched at 24^a 65 for engagement with one of the car axles.

A spring 27 normally acts upon the rock shaft 25 to swing the locking arm 24 upwardly into operative position. A crank arm 28 projects downwardly from the crank shaft 25 and is adapted to engage an abutment 29 when the track section 6 of the turntable is brought into engagement with the main track 2. The engagement of the crank arm 28 with the abutment 29 swings the locking arm 24 downwardly against the action of the spring 27 into inoperative position, and the car can then be moved from the turntable back upon the main track. The trip lever 14 locks the turntable in this position until another car is rolled into position upon the turntable. The latch means is then released, and the moment the track section 6 of the turntable is moved out of alinement with the main track 2 the locking arm 24 is automatically swung upwardly 75 into engagement with the axle of the car by the action of the spring 27, thereby locking the car in position upon the turntable until the turntable is again brought into position for moving the car back upon the main 80 track.

The mouth of the chute is effectively closed at all times, except when the ore or other material is being dumped into the chute from the cars. In mines and other 95 places where open chutes are commonly found, accidents are frequently occasioned by workmen falling through the unprotected chute openings, and these accidents could be completely avoided by the use of these safety 100 devices. The construction is simple and there are no complicated parts to get out of repair and cause trouble. Neither would it require a special attendant, since the turntable could be operated without difficulty by 105 the workman dumping the car.

Having thus described the invention, what I claim as new and desire to secure by Letters Patent, is:—

1. In a device of the character described, 110 the combination with a platform formed with a chute opening and having a track thereon, of a circular bed mounted upon the platform and having an opening registering with the chute opening, a turntable rotatably mounted upon the bed and formed with an opening adapted to be swung into and out of registry with the opening of the bed, and a track section upon the turntable arranged to be in alinement with the main track and form a continuation thereof when the turntable is in one position and to be moved out of alinement with the main track when the turntable is rotated to bring the opening thereof into registry with the chute 115 120 125

2. In a device of the character described, 130 the combination with a platform formed with a chute opening and having a main track thereon, of a circular bed mounted 135

- upon the platform and formed with an opening registering with the chute opening, a turntable mounted upon the bed, the opposing faces of the bed and turntable being 5 formed with seats having annular raceways therein, ball bearings within the raceways, said turntable being formed with an opening adapted to be moved into and out of registry with the chute opening, and a track 10 section arranged upon the turntable and adapted to be in alinement with the main track and form a continuation thereof when the turntable is in one position and to be swung into a position at angles thereto when 15 the turntable is rotated to bring the opening thereof into registry with the chute opening.
3. In a device of the character described, the combination with a platform formed with a chute opening and having a track 20 thereon, of a bed arranged upon the platform and formed with an opening registering with the chute opening, a turntable rotatably mounted upon the bed and formed with an opening adapted to be moved into 25 and out of registry with the chute opening, a track section arranged upon the turntable to be swung into and out of alinement with the main track and the chute opening being closed by the turntable when the track 30 section is in alinement with the main track, latch means for locking the turntable against rotation when the track section is in alinement with the main track, and means actuated by a car moved upon the track section 35 for releasing the latch means.
4. In a device of the character described, the combination with a platform formed with a chute opening and having a track thereon, of a rotatably mounted turntable 40 formed with an opening adapted to be swung into and out of registry with the chute opening, a track section arranged upon the turntable to be swung into alinement with the main track, the said track section being moved to a position at angles thereto when the turntable is rotated to bring the opening thereof into registry with the chute opening for dumping the contents of a car through the chute opening, means 45 for locking the turntable against rotation when there is no car thereon, and means for locking the car against movement on the turntable when the track section thereof is swung out of alinement with the main track.
5. In a device of the character described, the combination with a platform formed with a chute opening and having a track thereon, of a rotatably mounted turntable provided with an opening adapted to be 50 moved into and out of registry with the chute opening, a track section arranged upon the turntable to be in alinement with the main track when the chute opening is closed by the turntable and to be at angles to the main track when the opening of the 55 turntable is in registry with the chute opening, latch means locking the turntable against movement when the track section is in alinement with the main track, means actuated by a car moved upon the turntable for releasing the said latch means, locking means for holding a car against movement upon the turntable, and means for rendering the said locking means inoperative when the track section is in alinement with the main track.
6. In a device of the character described, the combination with a platform formed with a chute opening and having a track thereon, of a rotatably mounted turntable 60 formed with an opening adapted to be moved into and out of registry with the chute opening, a track section arranged on the turntable to be in alinement with the main track when the chute opening is closed and at an angle thereto when the chute opening is open, a rock shaft upon the turntable, a locking arm projecting from the rock shaft, means for normally swinging the locking arm into engagement with the car 65 to hold the car against movement, a crank arm projecting from the rock shaft, and an abutment arranged in the path of the crank arm for coöperation therewith to swing the locking arm into inoperative position when 70 the track section is in alinement with the main track.
7. In a device of the character described, the combination with a platform provided with a chute opening and having a track thereon, of a rotatably mounted turntable 75 provided with an opening adapted to be turned into and out of registry with the chute opening, a track section arranged upon the turntable to be moved into and out of alinement with the main track, the chute opening being closed by the turntable when 80 the track section is in alinement with the main track, a latch lever pivotally mounted upon the turntable for locking the turntable against rotation when the track section is in alinement with the main track, means normally holding the latch lever in operative position, and a trigger rigid with the latch lever and projecting upwardly into 85 the path of the car for automatically moving the latch lever into inoperative position when a car is moved upon the turntable.
- In testimony whereof I have signed my name to this specification in the presence of 90 two subscribing witnesses.
